WALTER C. SUTTON, OF CLEVELAND HEIGHTS, OHIO, ASSIGNOR TO THE LINDSAY WIRE WEAVING COMPANY, OF CLEVELAND, OHIO, A CORPORATION OF OHIO

MEANS FOR FEEDING A WIRE THROUGH A FURNACE

Application filed October 11, 1929. Serial No. 398,865.

This invention relates to a method and apparatus for feeding wires through an annealing furnace. Bronze wires which are used in the manufacture of belts for paper making machinery must be accurately annealed so as to obtain the desired degree of elasticity and hardness. One form of machine for accomplishing this result comprises an electric furnace with guide tubes, which extend through the furnace. The wires which are to be annealed are led from a bobbin rack through the tubes, and are wound on spools after they have passed through the furnace. The degree of heat, and speed of wire movement are adjusted to produce a desired degree of temper, while the wire moves continuously through the furnace. Frequently the wire breaks or is interrupted during the annealing operation.

One cause for the interruption of wire movement is the fact that the spool will hold a much smaller quantity of wire than the bobbin. Another cause is due to the imperfections which may exist in the wire. Upon the interruption of wire movement through the furnace, the practice has been to attach the bobbin end of the broken wire to a straight wire and then to feed the straight wire through the tube. The intense heat of the furnace however, not only makes the feed wire too hot to handle with the bare hands, but necessitates thereafter, a withdrawal of the feed wire, which obviously requires considerable time on the part of the operator, who normally is stationed only at the spool end of the apparatus.

An object of the present invention, therefore, is to provide a method of feeding wires through an annealing furnace so as to overcome the difficulties and objections mentioned, and to facilitate the operation of the furnace so as to permit the continuous annealing of wires in a satisfactory manner by only one operator. A further object is to provide an apparatus which may be easily used in existing furnace equipment.

Referring now to the drawings, Fig. 1 is a side elevation of an electric annealing furnace equipped with my invention; Fig. 2 is a vertical section taken on the line 2—2 in

Fig. 1; Fig. 3 is an enlarged view partly in section of the apparatus adjacent the point where the wires enter the furnace; and Fig. 4 is a similar view showing the connection between the wires after the point of connection has been moved slightly into the furnace tube.

I have indicated in the drawings, the outline of an electric furnace at 10 with a bobbin rack indicated in general at 11 at one end of the furnace, and a spool rack 12 at the opposite end of the furnace. The wire to be annealed is passed from a bobbin into one of the tubes 13 which extend through the furnace and project beyond each end thereof, and thence onto a spool on the winding rack. The apparatus is usually manipulated by one operator, who stands at the winding end and replaces the spools as soon as they are filled. As the capacity of the bobbin is many times that of the spool, the attention of the operator at the bobbin end is only required for relatively short periods to replace the bobbins or to feed broken wires through the tubes.

To feed the wires, which are to be annealed from the bobbin and through the furnace to a point where they are accessible for attachment to spools, without requiring the operator to leave the winding end of the apparatus for an objectionable length of time, and without inconvenience to the operator, I provide a feeding wire 15 in the nature of an endless belt, which extends through each furnace tube, and thence back preferably beneath and outside the furnace. Each wire has two shoulders in the form of loops or eyes 16 and 17, through which the end of the wire to be fed through the furnace may be attached. Such attachment, as shown in Fig. 3, is effected by looping an end 18 through the eye and giving it a turn or two around itself, so as to hold it temporarily to the endless wire while it is moving through the furnace. During such passage, the feed wire is maintained taut by a tensioning device which acts upon it outside the furnace. One form of such device comprises a guide sheave 20, which is mounted on an arm 21. The arm in turn may be pivoted, as at 22, to the fur-

nace frame and above the lower reach of the belt whereby the weight of the arm and sheave acts automatically to maintain the desired degree of tension upon the belt.

70 The material of which the endless wire is made must be able to withstand the highest heat at which the furnace is operated, as part of the wire remains stationary in the furnace until it is again required for feeding 75 purposes. I have found that a nichrome wire with 60% nickel and 12% chromium and the balance iron is suitable for the temperature of 1600 degrees F., at which the furnace is normally operated.

10 While one part of the feeding wire is within the furnace and is subjected to the heat, the remaining part in the preferred form is exposed to the atmosphere, and hence is reasonably cool so that it may be easily handled 15 by the operator during the feeding operation. In practice, one loop is always near the bobbin end of the belt, where it is easily accessible for connection with the bobbin wire. The operator then reaches under the bank of 20 wires, and pulls the feeding wire until the loop at the opposite end is brought to the bobbin end of the machine. The operator then passes to the opposite end of the furnace and moves the bobbin wire and attaches 25 it to the spool. This entire procedure can readily be accomplished while the annealing operation is continued on the other wires.

30 By means of the present invention, the feeding or lead-in wire is always accessible 35 for immediate use, and is capable of being conveniently handled by the operator, so as to complete the feeding operation in a minimum period of time.

I claim:

40 1. In combination, a wire annealing furnace, means for moving the work to be annealed relatively fast through the furnace, an endless feed wire extending through the furnace, part of the feed wire being inside the 45 furnace and part being outside thereof, and the feed wire being adapted to remain stationary while the work wire is moving through the furnace during the annealing operation, and means on the feed wire for attaching the work wire thereto, whereby the 50 work wire may be threaded through the furnace.

55 2. In combination, a wire annealing furnace having a wire receiving tube extending therethrough, an endless feed wire having a portion thereof extending through the tube and having the remaining portion disposed outside the furnace, said wire having a plurality of shoulders thereon for dividing it into 60 two substantially equal parts, said shoulders providing abutments for attachment to the end of a warp wire, whereby the feed wire may be propelled through the furnace for threading the warp wire therethrough, the feed wire being adapted to remain sta-

tionary at the completion of the threading operation and thereafter while the work wire is moving through the furnace, whereby the feed wire is in position for attachment of the work wire thereto, in the event of breakage of the work wire during the annealing operation.

75 3. A method of feeding a wire to be annealed through an annealing furnace, comprising arranging an endless wire with reference to the furnace so that a portion of the wire extends through the furnace in substantial parallelism with the work wire and is comparatively hot while the remaining portion extends outside the furnace and is comparatively cool, attaching one end to be annealed to the endless wire adjacent the inlet end of the furnace, whereby an operator may grasp the comparatively cool part of the endless wire and thereby propel the wire to be annealed through the furnace, and whereby the feed wire may remain stationary and disconnected from the work wire, while the work wire is in motion during the annealing operation.

80 4. In combination, a wire annealing furnace, a bobbin at one end thereof, a wire winding device at the other end thereof, means for operating the winding device to propel wire from the bobbin through the furnace and onto said device, an endless feed wire extending through the furnace and having a portion thereof extending substantially parallel to the path of the wire to be annealed, said feed wire having another portion thereof disposed outside the furnace and being sufficiently small that the outside portion is cool enough to handle while the furnace is in operation, said endless wire being normally stationary but adapted selectively to engage the wire to be annealed, and to propel such wire through the furnace at the initiation of the annealing operation, and thereafter to remain stationary while the work wire is moving through the furnace.

85 In testimony whereof, I hereunto affix my signature.
